UNITED STATES PATENT OFFICE

1,934,142

RAIL FASTENER

Franklin B. Rager, Johnstown, Pa.

Application April 12, 1932, Serial No. 604,807
Renewed September 20, 1933

2 Claims. (Cl. 238—195)

This invention relates to railway joints and equipment and it has more particular reference to an improved rail chair fastener which may be utilized as a rail joint for connecting the ends of abutting rail sections, or employed at a point between rail joints to prevent spreading of rails.

The invention is primarily designed to eliminate, as far as is practical, spreading of rails particularly at points referred to as track curves.

In carrying the inventive conception into practice, I have evolved and produced a novel selection and appropriate co-ordination of parts mechanically organized to withstand stress and strain and to afford firm anchorage of the rails on adjacent supporting ties.

In the accompanying drawings, wherein like reference characters are employed to designate like parts throughout the same:

20 Figure 1 is an inside elevational view of the invention used as a rail joint.

Figure 2 is a top plan view thereof.

Figure 3 is an outside elevational view.

25 Figure 4 is a transverse section taken on the plane of the line 4—4 of Figure 1.

Figure 5 is a perspective view of one end of the fastener removed from the tie.

As before stated, the invention may be used for joining the ends of rail sections or may be employed as an anchoring chair between the ends of rail sections whichever is preferred. The construction is the same, irrespective of the placement of the invention.

In the drawings, numeral 6 designates a conventional rail, the numeral 7 represents an ordinary cross tie. As depicted in Figure 5, the improved device is primarily made up of two companion sections or parts distinguished by the numerals 8 and 9 respectively.

40 The main section 8 is in the form of a relatively heavy metallic casting which is fashioned to provide an anchoring base 10 of rectangular plate-like form. This is provided at suitable points with spike holes 11. Moreover, the underside thereof is fashioned to provide suitable tie contacting shoulders 12.

Along one longitudinal edge the section 8 is formed with a relatively thick heavy member 13 which may be conveniently referred to as a rail abutment and it possesses the cross sectional shape represented in Figures 4 and 5 to conform to the portions of the web and base flange of the rail with which it co-operates. The relatively removable part 9 is cast as a separate unit and may be distinguished as the secondary sec-

tion merely as a matter of convenience of description.

This part 9 comprises a web abutment plate 14 which co-operates with the abutment 13 but bears against the opposite face of the web of the rail as seen in Figure 1. Thus these two parts 13 and 14 are disposed against opposite sides of the rail in proper clamped relationship. The numerals 15 designate suitably curved connecting members which afford connection between the plate 14 and the attaching base 16 of this particular unit.

The base 16 is provided on its underside with longitudinally spaced tapered retaining projections 17 which fit down into correspondingly shaped depressions 18 formed at the top of the main base plate 10. Thus the two parts 16 and 10 are secured firmly together in superposed relationship through the medium of bolts 19. As a further feature of reinforcement, I provide 75 rectangular washers 20 which are arranged between the connecting members 15 as shown in Figure 1 and secured to the rail clamping abutments 13 and 14 through the medium of bolts 21.

80 It is evident that the primary part 8 is securely spoked and anchored on the cross ties after which the rail 6 is slipped into place. Then the removable clamping section 9 is bolted down on the plate 10, the washers 20 put in position 85 between the connecting members 15 and then the bolts 21 passed through the part 20, 14, and 13 to provide the secure rail maintenance assembly represented in Figure 4.

By securely attaching the device to the cross 90 ties, and clamping the rail therein, positive maintenance of the rail is insured, preventing longitudinal slippage of the rail or transverse spreading of companion rails. Consequently the invention affords proper facilities for adequate 95 rail anchorage and maintenance.

It is thought that the description taken in connection with the drawings will enable a clear understanding of the invention to be had. Therefore, a more lengthy description is thought 100 unnecessary.

While the preferred embodiment of the invention has been shown and described, it is to be understood that minor changes coming within the field of invention claimed may be resorted to 105 if desired.

I claim:

1. A rail fastener of the class described comprising a device including main and supplemental sections, the main section comprising a 110

casting made to provide a substantially rectangular tie plate, said tie plate being fashioned on its underside to provide shoulders to engage adjacent portions of the cross ties, said tie plate being formed with an upstanding relatively fixed rail abutment, and formed along the opposite longitudinal edge in its upper side with tapered depressions forming keeper seats, the supplemental section comprising an attaching plate superimposed upon the tie plate and formed on its underside with tapered projections fitting into said keeper seats, and further formed with a rail abutment plate to contract the adjacent face of the web of the rail, together with longitudinally spaced connecting members affording a rigid connection between the attaching plate and rail web contacting plate.

2. A rail fastener of the class described comprising a two-part structure including main and supplemental sections, the main section comprising a single casting including an elongated rectangular tie plate having apertures for accommodation of spikes adapted to be imbedded in the underlying ties, said plate being formed along one longitudinal edge with a relatively

heavy and thick vertically extending member fashioned to accommodate one-half portion of the base flange of the rail and to provide a rigid abutment plate to contact the adjacent face of the web of the rail, the supplemental section constituting a separately cast unit including an attaching base adapted to be bolted in superposed relation along the opposite longitudinal edge of said tie plate, said attaching base being formed on its underside with longitudinally spaced tapered lugs, and said tie plate having recesses receiving said lugs, said supplemental unit further including a vertical abutment plate to engage the opposite face of the web of the rail and joined to said attaching base by longitudinally spaced connecting members, said attaching base being proportioned in width to abut the adjacent longitudinal edge of the base flange of the rail, bolts securing the attaching base firmly against the tie plate, washers arranged between the connecting members, and clamping bolts passing through the washers and abutment plates of the respective sections for securing the rail firmly therebetween.
